(57) **CLAIM**

The ornamental design for a laundry detergent holder, as shown and described.

DESCRIPTION

FIG. 1 is a top, front, perspective view of a laundry detergent holder showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a reference view thereof.

The broken lines showing details in FIGS. 7 and 8 are included for the purposes of defining the bounds of the claim and of showing environmental portions of the laundry detergent holder and form no part of the claimed design.

1 Claim, 5 Drawing Sheets

FIG. 1

FIG. 2

FIG. 3

FIG. 4

FIG. 5

FIG. 6

FIG. 7

FIG. 8
